C. R. HAUSER.
CYLINDER GRINDING APPARATUS.
APPLICATION FILED MAR. 11, 1920.

1,359,699.

Patented Nov. 23, 1920.

UNITED STATES PATENT OFFICE.

CHARLES R. HAUSER, OF DENVER, COLORADO.

CYLINDER-GRINDING APPARATUS.

1,359,699.

Specification of Letters Patent. Patented Nov. 23, 1920.

Application filed March 11, 1920. Serial No. 365,052.

To all whom it may concern:

Be it known that I, CHARLES R. HAUSER, a citizen of the United States of America, and a resident of Denver, county of Denver, 5 and State of Colorado, have invented certain new and useful Improvements in Cylinder-Grinding Apparatus, of which the following is a full and clear specification.

The object of this invention is to provide 10 a simple apparatus which may be attached to and operated in an ordinary metal-working lathe and which will efficiently and truly grind the interior surfaces of engine cylinders, as more fully hereinafter set forth.

15 In the drawings—

Figure 1 is a view partly in side elevation and partly in longitudinal section;

Fig. 2 is a side elevation;

20 Fig. 3 is a transverse section on the line 3—3 of Fig. 1;

Fig. 4 is a transverse section taken through the motor casing and counter-weight;

25 Figs. 5, 6, 7 and 8 are detail parts hereinafter specifically described.

25 The figures of the drawings illustrate the various details of the invention in its preferred form.

Referring to the drawings annexed by reference-characters, *a* designates a solid cylindrical metal bar which is adapted to be supported at its ends respectively in the tail-stock and head-stock of a lathe, so as to be rotated by the usual lathe mechanism, this bar being provided at each end with a central recess *b* for the usual lathe center. 30 Mounted in a recess at one end of this bar is an electric motor *c*, this motor being rigidly fastened to the bar by suitable screws *d*. Diametrically opposite the motor, the bar is 35 provided with a counter-weight *e* which is fastened in any suitable manner, this counter-weight serving to balance the bar in its axial rotation and thus avoid undue vibration or wobbling of the bar.

40 45 The current for the motor is received through a pair of contact-rings *f* carried near one end of the bar *a*. The shaft of the motor is connected by a universal joint to a propeller-shaft *g* which lies in a longitudinal groove *h* formed along one side of the bar *a*, the inner end of this propeller-shaft *g* being connected by another universal joint to a shaft *i* which is journaled in suitable bronze bearings *j* mounted in a 50 pedestal-block *k* fitted in said groove *h* and adapted to be radially adjusted by means

of a series of set-screws *l*, another series of screws *m* being employed at the side to hold the pedestal in its radially adjusted position. The pedestal, it will be understood, 60 fits the flat straight walls of the groove *h* nicely so that in the operation of the apparatus the shaft *i* will be held true and steady. The inner end of the shaft *i* has affixed to it the grinding-wheel *n* which runs in a 65 laterally-enlarged pocket *o* formed at the extreme inner end of the groove *h*, said grinding-wheel having its periphery projecting more or less beyond the annular periphery of the carrying-bar *a*.

70

It will be observed that when the carrying-bar *a* is mounted in the lathe, it will be rotated by the usual mechanism of the lathe, and that during this axial rotation of the bar the grinding-wheel will be rapidly rotated by the motor, thus giving to the grinding-wheel a planetary motion. It will be observed, therefore, that this apparatus is 75 extremely simple in construction and operation and adjustment and that a special feature of advantage lies in the fact that it may be readily operated in any lathe of the proper size. Of course, it will be understood that the cylinder is mounted upon the usual lathe-saddle and is automatically fed 80 along the lathe-bed in the usual manner during the rotation of the grinding-wheel.

It will be understood that the pedestal or spindle-block *h* may be adjusted as well as locked in its adjusted position by any 90 suitable means. I prefer the use of a plurality of screws *l* for radially adjusting the block, and a plurality of additional screws *m* for engagement with opposite sides of the block for assisting in holding it in its position. The screws *l* will be journaled rotatably in the bar *a* and will have their inner ends engaged in threaded holes in the bottom of the spindle-block; and these screws *l* will be held against longitudinal 95 movement by lateral set-screws *p* tapped tangentially into the bar *a* and having a smooth reduced inner end *q* which enters an annular groove in the screw *l*. These small screws *p* will be headless and will be 100 properly counter-sunk in the bar *a*, and by tightening up these screws it will be seen that the screws *l* will be locked against rotation. To measure the adjustment of the pedestal or spindle-block, I may form a circular graduated scale *r* on the bar *a*, around the head of each screw *l*, thereby enabling 110

me to make not only a fine adjustment but also a predetermined adjustment of the pedestal block.

To insure accurate radial guidance of the 5 spindle-block *k*, the block is provided at opposite sides with grooves *r'* in which work the inner ends of the binding screws *m*. The groove *h* in the supporting-bar is deepened at its inner end and this pedestal or spindle-block fits in this depression, one end of the 10 block abutting against a shoulder *s* and the other, reduced, end of the block abutting against the shoulder *t* formed at one side of the enlarged recess *o*. In this manner, the 15 pedestal-block is assured not only of accurate radial movement in its adjustments, but is also insured against longitudinal movement of the carrying-bar, thereby contributing materially to accuracy of work. Any 20 suitable means may be employed for supplying current to the motor. The means disclosed consists, as stated, of two contact-rings *f* which are mounted on an insulating band *u* affixed to the bar *a* and connected respectively to the binding-posts of the motor 25 by suitable wiring *v*. The current is supplied to the contact-rings *f* by means of a pair of clamp-brushes each comprised of a pair of grooved jaw-bars *w* adapted to engage over the contact-ring, these jaws being pivoted together at *x* and being held resiliently clamped upon the contact-ring by means of a spring *y*, one of the jaws being extended at *z* for attachment, by clamps or 30 otherwise, to a stationary part of the lathe structure, an insulating piece *a'* being provided for convenience in handling the brush.

The nature and scope of the invention

having been thus indicated and its preferred embodiment having been specifically described, what is claimed as new is:

1. In a lathe attachment of the class set forth, a bar adapted to be supported in and rotated by the lathe-stocks, an electric motor mounted on the bar at one end and means 40 for supplying current to the motor during the rotation of the bar, a grinding-wheel carrying-shaft journaled in adjustable bearings mounted in a groove in the bar and adapted to be rotated by said motor. 50

2. In a lathe attachment of the class described, a bar adapted at its ends for attachment to the usual lathe-stocks so as to be axially rotated thereby, said bar being provided with a longitudinal groove terminating at each end in a pocket or recess, an electric motor mounted in the recess nearest the end of the bar, a grinding-wheel-shaft mounted in adjustable bearings in said groove and having its grinding-wheel located in the other recess, this shaft being connected to the shaft of the motor, and a counter-weight arranged on the bar diametrically opposite the motor. 55

3. A cylinder-grinding apparatus in the 60 form of a lathe attachment embodying a bar adapted to be received in a lathe and rotated thereby, said bar carrying an electric motor and a radially adjustable grinding means operated by said motor, and 65 means for supplying current to the motor during the rotation of the bar. 70

In testimony whereof I hereunto affix my signature.

CHARLES R. HAUSER.
